UNITED STATES PATENT OFFICE.

THOMAS A. SAMMONS, OF DAYTON, OHIO.

GAS-ENGINE.

No. 881,628.

Specification of Letters Patent. Patented March 10, 1908.

Application filed October 9, 1905. Serial No. 282,609.

To all whom it may concern:

Be it known that I, THOMAS A. SAMMONS, citizen of Dayton, residing at corner East Third and Madison streets, in the county of Montgomery and State of Ohio, have invented certain new and useful Improvements in Gas-Engines, of which the following is a specification.

This invention relates to improvements in gas engines, and has among its objects to provide such devices as will automatically shift from a four-cycle operation to an air pump operation comprising simply alternate operations of the intake valve and the exhaust valve without compression or ignition upon alternate reciprocations of the cylinder piston; also to provide certain novel arrangements of the valves and the actuating mechanism therefor; further, to provide certain improvements in the ignition or sparking devices; and also to provide certain other improvements incidental to carrying out the above mentioned objects.

The preferred form of embodiment of mechanisms for accomplishing the above objects will now be described, with reference to the accompanying drawings, of which:

Figure 1 represents a side elevation of the engine to which these improvements are applied; Fig. 2 represents an end elevation of the machine showing the valve mechanisms and their controlling devices; Fig. 2^a is a detail of parts shown in Fig. 2. Fig. 3 represents a detail side elevation of part of the valve mechanism, particularly the exhaust valve; Fig. 4 represents a detail sectional view on the line 4—4 of Fig. 2 looking in the direction of the arrow crossing said line; and Figs. 5, 6, 7 and 8 represent detail views of parts of the valve operating and controlling mechanisms.

The supporting framework 9 (see Fig. 1) for the engine comprises at one end thereof two upright supports 10, and in each one of these supports is journaled a fly-wheel shaft 11. The shaft 11 (shown in Fig. 1) is journaled in the near support 10 and its fly-wheel is shown removed for the sake of clearness, being of the same size and shape as the fly-wheel 12 which is shown in said figure and is mounted upon a shaft which is journaled in the other support opposite the support which is seen in Fig. 1. To the shaft upon which the fly-wheel 12 is mounted an eccentric 13 is also made fast, being on the opposite side of the supporting standard from the fly-wheel

12; and similarly an eccentric 14 is mounted on the shaft 11 inside of the supporting standard 10, to the outer end of which shaft 11 is attached the other fly-wheel which, as above stated, is shown removed. In order to connect these two sets of fly-wheels and eccentrics together so that they will move as one system, the two eccentrics are pinned together by means of a pin 15 so that the eccentrics and fly-wheels all revolve together upon their shafts 11. The shortest radius of the eccentric 13 is set opposite to the longest radius of the eccentric 14 and vice-versa as shown clearly in Fig. 1. A pin 15 extends between said eccentrics and to said pin is attached the outer end of the piston rod 16 attached at its inner end to the piston head 17, contained in the cylinder 18.

Pivoted to the framework of the engine at 75 20 is a valve operating lever 21 having at its rearward end an anti-friction roller 22 engaging the periphery of the eccentric 14. There is an exactly similar valve operating lever 23 (see Fig. 2) which extends under the 80 other eccentric 13, and for convenience the right-hand side of the engine will be spoken of as the side shown in Fig. 1 or the side shown at the right in Fig. 2. These right and left valve operating levers 21 and 23 are 85 arranged to depress and rise exactly alternately by their respective eccentrics, and it will be clear from Fig. 1 that the rearward end of each of these levers is depressed and raised again to normal position upon one 90 complete revolution of the fly-wheel and eccentrics, and these alternate operations are used to operate the various valves and the spark device as will now be described.

On the forward end of the lever 21 is 95 pivoted a pawl 30 drawn into the position shown in Fig. 1 by a spring 31 which of course also serves to pull down on the forward end of the lever 21 to keep the roller 22 in contact with its eccentric 14. This 100 pawl 30 has a nose 32 which normally lies directly below the stem 33 of an air valve, the head 34 of which valve is broadened out to seat over the air port 35. The pawl 30 also has a rearwardly extending foot 36 105 which normally stands below the stem 37 of a fuel valve, the cap 38 of which seats upon the upper portion of the fuel port 39 so as to close the port when the valve is dropped to lower position. Springs 45 maintain these 110 valves normally in lower seated positions closing their respective ports. As shown in

Fig. 4, the fuel and air ports join into the same chamber to be properly mixed. Thus it will be seen that when the forward end of the valve lever 21 is raised, the nose 32 will raise the air valve 34 and the foot 36 will raise the fuel valve. The time of contact of the pawl 30 with these two valves is so arranged that the pawl strikes the air valve shortly before it does the fuel valve so as to admit air before the fuel is admitted and thus cause a little suction of the air to assist in drawing in the fuel; and similarly the fuel valve seats before the air valve seats, and this arrangement makes it possible to control more definitely the supply of fuel which enters the valve. Fig. 4 shows both valves lifted by the raising of the pawl 30.

The exhaust valve 40 (see Fig. 2) has a cap and stem similar to the air and fuel valves and a suitable spring 41 to hold the same seated, and this valve is lifted by means of a pawl 42 shown in Figs. 2 and 3 attached to the left-hand valve lever 23 and also shown in detail in Fig. 7. This pawl is also held in normal position by a spring 43 which also assists in holding the lever 23 against its eccentric 13 at its rearward end. When the forward end of the lever 23 rises, the pawl 42 strikes the stem of the exhaust valve 40 and lifts the same to permit the exhaust of the consumed gases, this, as above explained, taking place alternately with the simultaneous lifting of the air and fuel valves.

The spark or ignition device will now be described. Extending up into the interior of the cylinder is a rod 50 (see Fig. 2) at the lower end of which is a binding post 51 and at the upper end of which is a conical metal contact piece 52, the rod 50 being suitably insulated from the cylinder by a collar 53 and the cone 52 being seated upon a suitable insulating block 54. Also extending up into the cylinder is a vertically movable rod 55 which at its upper end has attached to it a curved flat spring 56, on the outer end of which spring is a cylindrical contact piece 57. This rod 55 is arranged to be reciprocated so that the contact piece 57 will be raised and then will be permitted to drop to strike the contact cone 52. The binding post 51 of the cone 52 has attached to it a suitable electric wire (not shown) which wire extends from the ordinary electric battery, the other wire of which battery is suitably grounded on the engine with which the contact cylinder 57 is of course electrically connected since not insulated in any manner and therefore after the cylinder 57 strikes the cone 52 the spring 56 will vibrate and a spark will take place upon separation of the cylinder from the cone which will explode the gases which have been taken in and compressed. The lower end of this spark rod 55 is cut down so as to engage a slot 60 (see Fig. 5) formed in a

projection 61 extending rearward from a bail or clevis 62 which as shown in Figs. 1, 3 and 4, is pivoted at opposite sides to the framework of the machine. The forward bar of this clevis has a lug 63 projecting downwardly from it, which lug normally stands directly above a nose 64 of the aforesaid valve operating pawl 30 so that when said pawl is raised, this clevis will also be raised. However when it is so raised, the clevis is latched upward and does not immediately descend with the descending of the pawl 30. This latching is effected by means of a pawl 70 (see Figs. 2 and 4), which pawl is formed with a nose engaging a pin 71 on the side of one of the arms of the clevis, so that when the clevis is raised the pawl will engage said pin and latch the clevis in upper position as shown in Fig. 4. This pawl 70 is pivoted to the frame of the machine at 72 and also pivoted at this same point is another pawl 73 which as shown in Fig. 8 has at its middle portion an enlarged slot through which extends the shaft of the thumb screw 74 which screws into a projection 75 extending from the aforesaid pawl 70 so that when said thumb screw is screwed in the pawl 73 will in effect be attached to the pawl 70 so as to swing therewith, and this enlarged bearing permits the adjustment of the pawl 73 with reference to the pawl 70 for the purpose of advancing the sparking as will later be described.

Pivoted upon a short shaft 140 extending from the side of the machine is a ratchet wheel 80 which it will be seen is provided with a succession of deep and shallow notches and long and short teeth, occurring alternately. The above mentioned pawl 73 extends downward so that its nose engages the periphery of said ratchet wheel. This ratchet wheel is rotated by an advance of one of its teeth at each operation of the valve lever 21, by means of a laterally extending rod 81 which is attached to the aforesaid valve operating pawl 30, so that each time the valve lever 21 is reciprocated, said rod will engage either a deep notch or a shallow notch of said ratchet wheel and advance the wheel a distance of one of said teeth; a retaining pawl 82 prevents reverse rotation of the ratchet wheel, and a spring 83 extending between said retaining pawl and said pawl 73 holds both the retaining pawl in engaging position and also holds the pawl 73 against the ratchet wheel.

The operation of these parts is as follows: Assuming that the engine is running "over" that is: in the direction of the arrow shown in Fig. 1, the valve lever 21 has been partially depressed when the eccentric 14 is in the position shown in Fig. 1, so that the pawl 30 is partly raised. As said pawl continues to rise, the air and fuel valves are lifted as above described, and the clevis 62, is also lifted; and the rod 81 engages a deep

notch on the ratchet wheel 80 and turns the same a distance of one tooth so that the pawl 73 rides over one of the short teeth and when the clevis is fully lifted, said pawl now 5 rests along the forward side of one of the long teeth in the position shown in Fig. 4. The clevis now being raised, the pawl 30 descends but the clevis remains latched up by said latching pawl 70. While the pawl 10 30 is going down, the aforesaid exhaust operating lever 23 is going up and would normally tend to operate the exhaust valve as previously described, but since the opening of the air and fuel valves has permitted a 15 charge to be introduced into the cylinder, this charge should now be compressed and the exhaust valve should not be operated. This is effected by reason of the fact that the clevis remains raised, and a projection 20 or toe 90 (see Figs. 3 and 5) extending downward from the left-hand side of the clevis has its lower end bent forward so as to act upon a pin 91 extending from the side of the aforesaid exhaust valve pawl 42 so as to 25 rock said pawl forward and out of alignment with the stem of the exhaust valve. Thus when the clevis remains raised in this position, the exhaust pawl 42 is disabled by the toe 90, and the exhaust valve misses a stroke, 30 so that the gas which has been drawn into the cylinder can be properly compressed. The exhaust lever 23 now descending the gas valve lever 21 now goes up again carrying the pawl 30 again upward and causing 35 its attached rod 81 to engage this time one of the short teeth of said ratchet wheel, but likewise advancing the ratchet wheel a distance of one tooth. However, since the pawl 73 has been resting along the side of one 40 of the long teeth, this advance movement of the ratchet wheel now causes this long tooth to cam the pawl 73 so far forward as to carry the latching pawl 70 also forward, the two pawls being attached together as previously 45 described, and thus the latching pawl 70 is freed from the pin on the side of the clevis and the clevis is free to drop under the tension of its spring 65 (see Figs. 2 and 3), and this dropping of the clevis causes the aforesaid spark contact cylinder 57 to strike 50 the contact cone 52 and cause a spark which ignites the compressed gas to cause an explosion to drive the piston forward. It was of course necessary however that when the 55 pawl 30 was raised this second time to drop the clevis and permit the sparking, that this pawl should not again operate the fuel and air valves. This is effected by reason of the fact that when the cross rod 81 is engaging 60 the shallow notch or the shorter tooth for this second upward movement of the pawl 30 (as shown in Fig. 6), the rod 81 is maintained so far forward that the pawl 30 is also maintained in a displaced forward position 65 so that its air valve nose 32 and its fuel valve

foot 36 are displaced from alignment with their respective valves (as shown in Fig. 6) so that these valves are not now operated by the pawl as it goes up. Likewise the clevis lifting nose 64 is thrown out of alignment 70 with its lug 63 so that the clevis is free to drop with this spring movement as above described. When the pawl 30 now descends and the exhaust operating lever 23 now rises for the second time, of course the clevis 75 62 having in the meantime dropped, the toe 90 no longer holds the pawl 42 displaced so that when the lever 23 raises, the pawl now acts upon the exhaust valve 40 and lifts the same so as to permit the gases to be forced 80 outward through the exhaust port 44.

It will be understood that when the pin 15 which joins the two eccentrics 13 and 14 is in the position shown in Fig. 1, and the fly-wheel is rotating in the direction shown by the arrow, that the fuel and air valve lever 21 is partially depressed and the pawl 30 is being carried upward to take in the mixture, and when the pin 15 reaches the top of the stroke, that is: in the position directly over 90 the shafts 11, the pawl 30 is raised to its highest position and the clevis locked up, and as the pin 15 continues to its next quarter revolution, the air and fuel valves begin to close and upon reaching the end of such 95 revolution, the piston is withdrawn to its fullest extent outward, and then as the piston goes backward of course the gas mixture is compressed in the ordinary manner and when the pin 15 has made one complete revolution back to the position shown in Fig. 1, the pawl 30 has begun to be raised for the second time preliminary to unlatching the clevis so as to cause the sparking, and it is desirable to have some means for adjusting 100 this time of sparking so that the explosion will take place at any desired interval in the period of compression within a certain range, this advancing and retreating of the sparking being of course well known in the art. Since 105 as above explained the sparking occurs when the clevis is dropped, and since the dropping of the clevis depends upon when the latch pawl 70 is released, this control of the sparking is effected by varying the time of release 110 of the clevis which is very simply performed by the slotted adjustment hitherto spoken of with reference to the pawl 73. As shown in Figs. 4 and 8, the pawl 73 is formed at its middle portion with the previously mentioned elongated slot 95 through which the shaft of the aforesaid thumb nut 74 (see Fig. 2) extends so that said pawl 73 may be first 115 properly adjusted and then fastened in position by screwing up the thumb nut, and by this adjustment the pawl is tripped forward sooner or later by the aforesaid long teeth of the ratchet wheel 80. That is: when the pawl is drawn furthest rearward, the long tooth of the ratchet wheel will force the pawl 120 125 130

73 outward sufficiently to trip the latch pawl 70 from engagement with the clevis at an early period in the rise of the valve operating pawl 30, whereas if the pawl 70 is adjusted to 5 its fullest extent forward (that is to the left, in Fig. 1), the long tooth will not so soon cam the pawl further forward to effect the dropping of the clevis and thus the time of 10 sparking will be delayed until the piston has become pretty well started outward on its stroke, and the aforesaid pin 15 is well along on its upward stroke. By this means, the 15 advancing or retreating of the spark may be accomplished at any time without requiring 20 the stopping of the engine. In connection with the sparking device it may here be stated that when the clevis 62 is in its lowest position, the upper end of the rod 55 which carries the contact cylinder 57 (see Fig. 2) is 25 resting upon the solid portion of the cylinder but the spring 56 holds the cylinder 57 away from the contact cone 52. When however the rod 55 is raised with the clevis and then dropped under spring tension, the spring 56 30 of course vibrates and the momentum of the cylinder 57 carries the same against the contact cone 52 to cause the spark, and then comes to rest out of contact with the cone. Owing to the conical shape of the contact 35 piece 52, the cylinder 57 strikes the cone with a wiping movement giving the wiping form of spark which is so desirable in mechanism of this sort to keep the contact surfaces bright and free from corrosion. This also 40 produces the spark by means of an impact or blow which has the necessary sliding movement between the surfaces but only momentarily so as not to produce the undue wear which is present in machines where 45 there is a steady sliding pressure between the contact making surfaces. Furthermore, the cone 52 can be rotated at any time so as to bring new surfaces to contact.

In order to stop the vibration of the cylinder 57 when the rod 55 is raised, a pin 97 (see Fig. 2) is provided which extends from any suitable part of the framework of the piston cylinder so that when the contact cylinder 57 is raised it will strike the pin 97 just 50 at the end of the up-stroke of the rod 55 so as to leave the contact cylinder free from vibration and thereby insure the same properly striking the cone 52 when the rod 55 drops.

In order to vary the strength of the blow 55 by which the contact cylinder 57 is made to strike the cone 52, and thereby vary the strength of the spark, the spring restoring power exerted on the clevis 62 is made adjustable; that is: the aforesaid restoring 60 spring 65 (see Figs. 2 and 3) carries at its upper end a hook 100 which may be made to engage any one of a series of pins 101 along the side of the left-hand arm of the clevis so as to exert greater or less restoring stress 65 upon the clevis and thereby causing the

movable contact cylinder 57 to drop with greater or less force upon the contact cone 52. This adjustment also has the marked advantage of being possible even while the engine is running.

The sequence of operation just described above with relation to the taking in of gas, the compression, explosion and exhaust, constitutes an engine of the four-cycle type. When however the engine running under this 70 four-cycle movement, develops too high a speed, automatic means are provided which will cut the engine down to a simple air pump operation operating alternately the air valve and then the exhaust valve without compression or ignition upon alternate reciprocations of the cylinder piston and this means will now be described. Upon the shaft 110 upon which the aforesaid ratchet wheel 80 is mounted, there is also mounted a pulley 111 75 (see Fig. 2) carrying a governor comprising governor balls 112 carried upon the outer ends of bell crank levers pivoted at 113, the vertical arms 114 of which bell crank levers press against a circular controlling disk 115 80 and since the same is loosely mounted on said shaft 110, said disk is then forced toward the ratchet wheel 80. Then when the ratchet wheel operating rod 81 (carried by the pawl 30 as above described) now comes down over 85 the forward side of one of the longer teeth of the ratchet wheel, the outer end of the rod is carried forward sufficiently so that the disk 115 can snap in by the side of the ratchet wheel 80 and thereby the rod 81 now 90 plays over the circumference of the disk 115 and cannot engage the teeth of the ratchet wheel 80. The effect of this is that when the valve operating pawl 30 now rises, it has been 95 displaced to its extreme limit of position forward, so that the projection 120 thereon is now directly under the air valve stem 33 and the fuel valve operating foot 36 is entirely 100 withdrawn from position to operate the fuel valve stem 37. The result is that the upward stroke of the pawl now simply operates the air valve to admit air into the cylinder without admitting any fuel; likewise since the clevis operating nose 64 of the pawl 30 105 has been displaced forward out of alignment with the clevis lug 63, the clevis is not raised and therefore no sparking takes place, and since the clevis is not raised the succeeding upward movement of the exhaust lever 23 110 results in the opening of the exhaust valve. It will be obvious that this alternate operation of the valve operating levers 21 and 23 115 now results in opening the air valve and then the exhaust valve so that there is simply a continuous flow of air through the cylinder 120 and the same is cooled down and the engine in effect transformed into an engine of a type comprising simply admission of air and exhaust of the same. This immediately of course reduces the speed of the engine but 125 130

the alternate air and exhaust valve operation will continue so long as the disk 115 remains in this displaced position engaging the pin 81. When the engine now slows down, of course the governor balls approach each other and the pressure of the arms 114 on the disk 115 is removed and the same moves out under suitable spring tension of the spring 115^a see Fig. 2^a; so as to free itself from the rod 81 and thereupon the next raising movement of the pawl 30 causes the rod to engage properly beneath one of the longer teeth of the ratchet wheel 80, that is: in one of the deep notches as shown in Fig. 1; and in such position, the four-cycle type again obtains with the sequence of operation of the valves as first explained. It will be obvious that when the rod 81 rides down over the forward side of one of the shorter teeth of the ratchet wheel 80, the end of the rod holds the disk 115 from being forced inward by the governor, that is: the valve pawl 30 must first rise to trip the clevis and allow the sparking to explode the gas before the change to the air pump operation is effected in the manner described; and thus this also leaves the engine ready to take fuel by engagement of the rod 81 under one of the longer teeth as soon as the controlling disk is returned to its normal outer position free from the rod 81.

By means of an adjustable collar 125 (see Fig. 2), and a thumb screw 126, the tension of the governor springs 127 may be increased or diminished by sliding the collar 125 laterally so as to control the speed of the engine at which the same shall shift to the air pump operation.

The successive raising and lowering of the valve operating lever 21 is also used to operate a gasolene pump if it is desired to use fuel of this form in the engine. This pump is shown at 130 in Fig. 2 and the piston 131 of the pump has laterally projecting forward from the same an arm 132 which extends over the left-hand extension of the aforesaid operating rod 81 carried by the pawl 30, so that as said pawl goes up and down its rod 81 will act upon the arm 132 to lift the pump piston 131, and piston being returned by suitable spring tension when the rod 81 drops. In order to adjust the length of stroke of the pump piston, a collar 133 is provided which surrounds the outside of the pump and may be adjusted at any height thereon by means of a thumb screw 134. The rearward side of this collar as shown in Fig. 3 carries an upright bar 135 upon the outer end of which is a shoulder 136 and the upper extension of the bar 135 is narrowed down to extend through an aperture in the rearward extension of the aforesaid arm 132. Thus by adjusting the collar 133 the extent of dropping of the pump piston is limited by engagement of the arm 132 with the shoulder 136, thus regulating the entire length of the

stroke of the piston; and if desired, the collar 133 may be adjusted so high up that the shoulder 136 continually supports the arm 132 of the pump piston and prevents the rod 81 from having any operative effect thereon. 70 This adjustment is necessary when it is desired to use ordinary gas as a fuel instead of gasolene, or at least a form of fuel which does not require the operation of any pump; and by means of such a device the change can be 75 made immediately from one form of fuel to the other as far as the question of the operating of the pump is concerned. It will also be observed that when the governor shifts the engine over to the alternate air and exhaust valve movement by means of the controlling disk 115, that the cross rod 81 on the operating pawl 30 will be moved so far forward as to miss the pump piston arm 132 so that the pump is not operated while the engine is running with this alternate air and exhaust valve movement, and is cut out with the cutting out of the fuel valve and the spark, thus saving wear on the pump when it is not necessary to have the same 90 working.

Since in some cases it is desirable to have the engine fly-wheel run reversely, or as it is sometimes expressed, run "under" instead of "over", the aforesaid bearings 95 shown in Fig. 1 are such as to permit this change without any manipulation of valves or connecting mechanisms. The shafts 11 when seated in their supporting standards 10 are held therein by journal blocks 140 which 100 are suitably screwed to the standards to maintain the shafts therein. By removing the pin 15 so that the piston rod can temporarily be disconnected from the eccentrics, and by also removing the journal blocks 140, 105 the entire system of fly-wheels and eccentrics can then be inverted so that the eccentrics will be reversed, that is: 14 will resume the place of 13 and vice-versa, and then by connecting up the piston rod with the pin 15, 110 the system will again be in operative condition, and the eccentrics as now placed will operate the valve operating levers 21 and 23 so that the engine will now run "under" that is: in the direction reversely to the direction 115 shown by the arrow in Fig. 1.

In order to balance the weight of the connecting rod 16, a weight 150 is fastened upon one of the eccentrics at the proper radial distance from the shafts 11 corresponding to the 120 radial distance of the pin 15, and this makes an evenly continued balance as the machine runs faster and faster whereas if the weight were placed upon the periphery of one of the fly-wheels, the weight would have greater 125 and greater overbalancing effect as the centrifugal force increased with the speed of the fly-wheels.

With reference to the above described arrangement of valves and operating devices 130

therefor, it may be pointed out that cams and gears for operating these various valves are entirely dispensed with and by this consolidation of the parts in the situations in 5 proximity to each other the entire valve mechanism may be operated with the greatest simplicity by means of these eccentrics and valve operating levers. And furthermore, the situation of the valve mechanisms 10 is such that no packing is necessary except for the cylinder head itself, thus eliminating the disadvantages arising from the necessity of packing various separate ports for the chambers.

15 While the form of mechanism here shown and described is admirably adapted to fulfil the objects primarily stated, it is to be understood that the invention is not confined to the one form of embodiment herein disclosed, 20 but is susceptible of embodiment in various forms, all coming within the scope of the claims which follow.

Another advantage may be mentioned with regard to the operation of this engine is 25 that when the fuel valve is cut out as above described, the air which is taken in and then forced out through the exhaust valve undergoes no compression as in the case of the style 30 of gas engines where the fuel intake misses and the air which is taken in has to be compressed on the return stroke of the piston, which compression of the air in itself serves to heat up the cylinder, and then this same heated air remains in the cylinder until another revolution has gone by when the exhaust valve operates to permit the expulsion 35 of this air. The present engine obviates this difficulty by permitting the immediate expulsion of the air without compression and 40 thus materially assists in cooling the cylinder.

With regard to the cutting out of the fuel valve, it may further be noted that when the valve cuts out by the operation of the controlling disk 115, this leaves one of the deep 45 notches of the ratchet wheel 80 ready to be engaged by the rod 81 the very instant the machine slows down enough to permit the controlling disk to return to normal position; 50 so that when the machine does slow down in this manner the engine immediately takes fuel without having to wait as in other gas engines until the proper revolution is arrived at in which to take in fuel; and thereby the 55 effective power of the engine is materially augmented.

Having thus described the invention, what is claimed as new is:

1. In a gas engine, the combination with a 60 cylinder, intake and exhaust valves, ignition means, and devices for producing a four-cycle movement of the engine, of means for automatically changing to an alternate intake and exhaust valve movement alone without 65 compression or ignition.

2. In a gas engine, the combination with a cylinder, intake and exhaust valves, ignition means, and devices for producing a four-cycle movement of the engine, of means controlled by the speed of the engine for automatically changing to an alternate intake and exhaust valve movement alone without 70 compression or ignition.

3. In a gas engine, the combination with a cylinder, intake and exhaust valves, ignition 75 means, and devices for producing a four-cycle movement of the engine, of a governor connected to the engine; and means connected with said governor for automatically changing to an alternate intake and exhaust 80 valve movement alone without compression or ignition when the speed is above a certain normal.

4. In a gas engine, the combination with a cylinder, of an intake valve; an ignition device; an exhaust device; means for operating the above devices to produce a proper sequence of in-take, compression, ignition, and exhaust; and means for automatically cutting out of operation the ignition device and causing alternate operation of the intake and the exhaust valves with alternate reciprocations of the cylinder piston when the speed is 85 above normal.

5. In a gas engine, the combination with a cylinder, of an intake valve; an ignition device; an exhaust device; means for operating the above devices to produce a proper sequence of in-take, compression, ignition, and exhaust; a governor connected with the engine; and means connected with said governor for automatically cutting out of operation the ignition device and causing alternate operations of the intake and the exhaust 90 valves with alternate reciprocations of the 100 cylinder piston.

6. In a gas engine, the combination with a cylinder, of an air valve for introducing air into said cylinder; a fuel valve; an exhaust valve; an ignition device; means for operating said valves and ignition device to cause the sequence of in-take of air and fuel, compression, explosion, and exhaust; and means controlled by the speed of the engine to automatically cut out of operation the fuel valve 110 and the ignition device and operate simply the air valve and the exhaust valve alternately without compression, to pump air through the cylinder when the speed rises above normal.

7. In a gas engine, the combination with a cylinder, and valves therefor, of a valve operating member; and a ratchet wheel having a succession of deep and shallow notches engaged by part of said operating mechanism 115 for controlling the operation of the valves.

8. In a gas engine, the combination with a cylinder, of a valve operating lever having an operating pawl mounted thereon; and a ratchet wheel engaged by an extension of 120 125 130

said pawl for controlling the operation of the valve operating pawl on the valves.

9. In a gas engine, the combination with a cylinder and fuel and air valves, of a valve operating lever having an operating pawl mounted thereon; and a ratchet wheel engaged by a part of said operating pawl for disabling said pawl or rendering the same effective on said valves.

10. 10. In a gas engine, the combination with a cylinder, of air and fuel valves therefor; a valve operating lever having an operating pawl mounted thereon formed with projections for engaging said valves and operating the same; a ratchet wheel formed with a succession of deep and shallow notches engaged by a projection extending from said pawl; and means for operating said lever for causing the pawl to operate the valves when said projection engages one of the ratchet wheel notches and miss the valves when the projection engages the succeeding notch.

11. In a gas engine, the combination with a cylinder, and valves therefor, of a valve operating device; a ratchet wheel engaged by a part of said operating device for controlling the operation of the valves; and a controlling disk coöperating with said part of said operating device and acting to control the valves independently of the ratchet wheel.

12. In a gas engine, the combination with a cylinder, and valves therefor, of a valve operating device; a ratchet wheel engaged by a part of said operating device for controlling the operation of the valves; a controlling disk coöperating with said part of said operating device and acting to control the valves independently of the ratchet wheel; and a governor connected with the engine for operating said controlling disk.

13. In a gas engine, the combination with a cylinder, of air and fuel valves therefor; a valve operating lever carrying a pawl formed with projections for engaging said valves; a ratchet wheel having teeth engaged by a projection on said pawl, said teeth being differently formed to control the operative position of said pawl; and a controlling disk for engaging said projection and maintaining the pawl displaced free from engagement with said ratchet wheel whereby to operate only the air valve.

14. In a gas engine, the combination with a cylinder, of air and fuel valves therefor; a valve operating lever carrying a pawl formed with projections for engaging said valves; a ratchet wheel having teeth engaged by a projection on said pawl, said teeth being differently formed to control the operative position of said pawl; a controlling disk for engaging said projection and maintaining the pawl displaced free from engagement with said ratchet wheel whereby to operate only the air valve; and a governor connected with

the engine for controlling the position of said disk.

15. In a gas engine, the combination with a cylinder, of an operating device; a movable frame actuated by said operating device; an exhaust valve and means for actuating the same; and means for controlling the operation of said exhaust valve actuating means upon the exhaust valve according to the position of said frame.

16. In a gas engine, the combination with a cylinder and valves therefor including an exhaust valve, of a valve operating device; a movable frame actuated by said operating device, said frame carrying a projection for disabling the operation of the exhaust valve when said frame is displaced from normal position.

17. In a gas engine, the combination with a cylinder, of air, fuel and exhaust valves therefor; an operating device for said air and fuel valves; a second operating device for said exhaust valve; a movable frame actuated by said first mentioned valve operating device; and means connected with said frame for disabling the effectiveness of the exhaust valve operating device.

18. In a gas engine, the combination with a cylinder, of air, fuel and exhaust valves therefor; a valve operating lever carrying a pawl for operating said air and fuel valves; a second operating lever carrying a pawl for operating said exhaust valve; a movable frame operated by said first lever; and means connected with said frame for disabling the pawl of said exhaust valve operating lever to prevent the operation of the exhaust valve when the frame is displaced from normal position.

19. In a gas engine, the combination with a cylinder and valves therefor, of two valve operating devices; and means for controlling the operation of one of said devices by the operation of the other.

20. In a gas engine, the combination with a cylinder and valves therefor, of a valve operating device; a movable frame actuated by said operating device; and an ignition device operated to cause ignition by the movement of said movable frame.

21. In a gas engine, the combination with a cylinder and valves therefor, of a valve operating device; a movable frame actuated by said operating device; means for latching said frame in displaced position; an ignition device connected with said frame; and means for releasing said frame to cause the ignition to take place.

22. In a gas engine, the combination with a cylinder and valves therefor, of a valve operating device; a movable frame actuated by said operating device; and a ratchet wheel engaged by said operating device for controlling the effectiveness thereof upon said movable frame.

23. In a gas engine, the combination with

a cylinder and valves therefor, of a valve operating device; a movable frame actuated by said operating device; means for latching said frame in displaced position; and a ratchet wheel engaged by said operating device for controlling the effectiveness of said operating device on said frame and also for causing the tripping of the latch for said frame.

10 24. In a gas engine, the combination with a cylinder and valves therefor, of a valve operating device; a movable frame actuated by said operating device; means for latching said frame in displaced position; a ratchet wheel engaged by said operating device for controlling the effectiveness of said operating device on said frame and also for causing the tripping of the latch for said frame; and an ignition device connected with said frame 15 and operated when the latch therefor is released.

25 25. In a gas engine, the combination with a cylinder and air, fuel and exhaust valves therefor, of a fuel and air valve operating device; an exhaust valve operating device; a movable frame actuated by said air and fuel valve operating device; an ignition device connected with said movable frame; means connected with said frame for disabling the 30 exhaust valve operating device when the frame is displaced from normal position; and a controlling device coöperating with said air and fuel valve operating device to cause the first operation of said valve operating device 35 to operate the air and fuel valves and also displace said movable frame whereby said exhaust valve is disabled, and the second operation of said air and fuel valve operating device to miss both of said valves and said frame.

40 26. In a gas engine, the combination with a cylinder and air, fuel and exhaust valves therefor, of a fuel and air valve operating device; an exhaust valve operating device; a movable frame actuated by said air and fuel

valve operating device; an ignition device connected with said movable frame; means connected with said frame for disabling the exhaust valve operating device when the frame is displaced from normal position; a controlling device coöperating with said air and fuel valve operating device to cause the first operation of said valve operating device to operate the air and fuel valves and also displace said movable frame whereby said exhaust valve is disabled, and the second operation of said air and fuel valve operating device to miss both of said valves and said frame; means for latching the movable frame in displaced position; and means for causing the release of said latch to permit the frame to return to normal position and thereby cause the sparking when said air and fuel operating device misses its operation.

27. In a gas engine, the combination with a cylinder and air, fuel and exhaust valves, therefor, of a fuel and air valve operating device; an exhaust valve operating device; a movable frame actuated by said air and fuel valve operating device; an ignition device connected with said movable frame; means connected with said frame for disabling the exhaust valve operating device when the frame is displaced from normal position; and a ratchet wheel having a succession of deep 75 and shallow notches coöperating with said air and fuel valve operating device to cause the first operation of said valve operating device to operate the air and fuel valves and also displace said movable frame whereby said exhaust valve is disabled, and the second operation of said air and fuel valve operating device to miss both of said valves and said frame.

In testimony whereof I affix my signature 85 in presence of two witnesses.

THOMAS A. SAMMONS.
